US0D1071721S

(12) **United States Design Patent** (10) **Patent No.:** **US D1,071,721 S**
(45) **Date of Patent:** **** Apr. 22, 2025**

(54) **WINE CASE**

(71) Applicant: **Barry Alexander**, Scottsdale, AZ (US)

(72) Inventor: **Barry Alexander**, Scottsdale, AZ (US)

(**) Term: **15 Years**

(21) Appl. No.: **29/895,012**

(22) Filed: **Jun. 15, 2023**

Related U.S. Application Data

(62) Division of application No. 29/747,078, filed on Aug. 19, 2020, now Pat. No. Des. 1,025,769.

(57) **CLAIM**

The ornamental design for a wine case, as shown and described.

DESCRIPTION

FIG. 1 is a front perspective view of a wine case;

FIG. 2 is a bottom perspective view thereof;

FIG. 3 is a top view thereof;

FIG. 4 is a bottom view thereof;

FIG. 5 is a right-side view thereof;

FIG. 6 is a front view thereof;

FIG. 7 is a rear view thereof; and,

FIG. 8 is a front perspective view thereof, shown with the top flaps closed.

The broken lines showing bottles in FIGS. 1 and 3 represent environmental structure. All other broken lines represent the bounds of the claim. The broken lines form no part of the claimed design.

1 Claim, 8 Drawing Sheets
